UNITED STATES PATENT OFFICE

168,422

TEXTILE FABRIC

Henry Rose, New York, N. Y.

Application October 25, 1951, Serial No. 17,109

Term of patent 3½ years

(Cl. D92—1)

To all whom it may concern:

Be it known that I, Henry Rose, a citizen of United States of America, resident of New York, in the county of New York and State of New York, have invented a new, original, and ornamental Design for a Textile Fabric, of which the following is a specification, reference being had to the accompanying drawing, forming part thereof.

In the drawing, the figure is a plan view of a textile fabric, showing my new design.

I claim:

The ornamental design for a textile fabric, substantially as shown.

HENRY ROSE.
